UNITED STATES PATENT OFFICE.

HENRY KASPAR, OF LYNCH, NEBRASKA.

DOUBLE-POINTED SAFETY-PIN.

No. 853,799.

Specification of Letters Patent.

Patented May 14, 1907.

Application filed March 20, 1906. Serial No. 307,087.

To all whom it may concern:

Be it known that I, HENRY KASPAR, a citizen of the United States, residing at Lynch, in the county of Boyd and State of Nebraska, have invented a new and useful Double-Pointed Safety-Pin, of which the following is a specification.

This invention relates to double pointed safety pins and has for its object to provide a simple, inexpensive and efficient device of this character having oppositely disposed piercing members or pins whereby two or more garments or parts of garments may be conveniently secured together.

A further object of the invention is to provide a double pointed safety pin in which the garment piercing members or points are disposed on opposite sides of the body portion and provided with suitable guards.

A still further object is to generally improve and simplify this class of devices so as to add to their utility and durability as well as to reduce the cost of manufacture.

With these and other objects in view the invention consists in the construction and novel combination and arrangement of parts hereafter fully described and illustrated in the accompanying drawings, it being understood that various changes in form, proportions and general assemblage of parts may be resorted to within the scope of the appended claims.

In the drawings forming a part of this specification, Figure 1 is a perspective view of a double safety pin constructed in accordance with my invention. Fig. 2 is a perspective view of the same with the terminal clamping members or guards detached. Fig. 3 is a plan view of a modified form of the invention.

Similar numerals of reference indicate corresponding parts in all the figures of the drawings.

The pin shown in the preferred form of the device is preferably constructed of a single piece of spring wire an intermediate portion of which is bent to form a spring coil 5 and thence bent laterally at 6 to form a second coil 7, the ends of the wire after the coils 5 and 7 are formed being extended laterally to form garment engaging members or pins 8 and 9 terminating in piercing points 10, as shown.

Embracing the coils 5 and 7 and preferably held in contact therewith by bending the sides of the metal as shown at 10' are clamp-

ing members or clips 11 each provided with an over-hanging arm 12 the side edges of which are bent downwardly to produce a guard for the reception of the point of the adjacent pin while the metal forming the opposite end of the clip is coiled or bent around the opposite pin at 13 to assist in preventing accidental displacement of said clips.

Attention is called to the fact that the springs 5 and 7 are coiled in the reverse direction and disposed one on each side of the connecting web or bar 6 so that said coils lie within the loops formed by the pins 8 and 9 and said connecting web or bar.

It will also be observed that by having the cylindrical portions 13 of the clamping members secured to the fixed ends of the pins they serve to limit the lateral movement of the free ends of said pins and also serve to reinforce and strengthen the pins at the points subjected to the most wear.

In Fig. 3 of the drawings there is illustrated a modified form of the invention in which pins are connected by a web or plate 14 the opposite ends of which are cut away at 14' to produce the guards 15, the pins in this case being formed of separate pieces of wire the ends of which are secured to the plate 14 by coiling the opposite side edges of said plate in contact therewith as shown at 16.

Having thus described the invention what is claimed is:—

1. A safety pin having diagonally disposed spring coils terminating in oppositely disposed garment piercing members, clips each consisting of a metal plate having one end thereof bent around a portion of the pin near the adjacent coil and its free end extended laterally to form an over-hanging arm the opposite edges of which are bent downwardly to produce a guard adapted to receive the point of the adjacent piercing member.

2. A safety pin having diagonally disposed spring coils terminating in oppositely disposed garment piercing members, clips each having one end thereof provided with means for attachment to a portion of the pin near the adjacent coil and its free end extended laterally to form a guard adapted to receive the point of the adjacent piercing member.

3. A safety pin formed of a single piece of wire bent to produce spring coils terminating in oppositely disposed garment piercing members, clips each consisting of a metal plate having one end thereof bent around one

of the piercing members near the spring coil thereof and its free end extended laterally to form an over-hanging arm the opposite edges of which are bent downwardly to form a guard adapted to receive the point of the opposite piercing member.

4. A safety pin comprising a body portion formed of a single piece of wire an intermediate portion of which is bent to form a spring coil and thence bent laterally to form a second coil, the ends of the wire after the coils are formed being extended to form

piercing members, and a clip secured to one end of each piercing member and having its intermediate portion embracing the adjacent spring coil and extended to form a guard for the point of the opposite piercing member. 15

In testimony that I claim the foregoing as my own, I have hereto affixed my signature in the presence of two witnesses.

HENRY KASPAR.
